FIG. 1.

FIG. 2.

INVENTOR

Harry T. Schakne

UNITED STATES PATENT OFFICE

110,224

DESIGN FOR A DRESS

Harry T. Schakne, New York, N. Y.

Application December 9, 1937, Serial No. 73,503

Term of patent 3½ years

To all whom it may concern:

Be it known that I, Harry T. Schakne, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the particular printed appliqués on the bolero portion, as shown.

I claim:

The ornamental design for a dress, substantially as shown, and described.

HARRY T. SCHAKNE.
